MODULATION INDICATING DEVICE

George W. Fyler, Schenectady, N. Y., assignor to
General Electric Company, a corporation of
New York

Application March 14, 1934, Serial No. 715,467

5 Claims. (Cl. 179—171)

My invention relates to percentage modulation indicating devices, or modulation alarms, and more particularly to such a device incorporating a gaseous conduction device capable of passing 5 a large current in response to occurrence of predetermined percentages of modulation.

An object of my invention is to provide such a device which is capable of response at all times with equal accuracy and which is actuated only 10 when the percentage of modulation is in excess of a predetermined value.

A further object of my invention is to provide such a modulation indicating device in which the accuracy of the reading or measurement of the 15 percentage of modulation increases as the percent modulation to be indicated increases.

The novel features which I believe to be characteristic of my invention are set forth with particularity in the appended claims. My invention 20 itself, however, both as to its organization and method of operation, together with further objects and advantages thereof may best be understood with reference to the following description taken in connection with the accompanying drawing 25 in which Fig. 1 represents an embodiment of my invention, and Fig. 2 represents a modification thereof.

Referring to Fig. 1 of the drawing, I have indicated therein an antenna 1 and an inductance 30 coil 2. These elements may comprise the output circuit of a transmitter in connection with which my invention is to be employed.

The modulation alarm, or indicating device, in accordance with my invention, comprises a suitable 35 electron discharge device 3, which is one of the gaseous conduction type having a plurality of electrodes surrounded by an attenuated gaseous medium, such as neon, argon, or mercury vapor. The anode circuit of this discharge device is supplied with operating potential from a unidirectional source, which may be connected to the 40 conductors 4, and which is indicated on the drawing by plus and minus signs. The positive side of this source is connected through the contacts 45 and winding of a relay 5 and limiting resistor 6 to the anode of the discharge device while the negative side is connected to ground. A potentiometer 7 is connected across this source and an intermediate point thereon is connected to the 50 cathode of the discharge device. The grid of the discharge device is connected through a resistance 8, inductance 9, and potentiometer 10 to the negative side of the source whereby both 55 anode and bias potentials for the discharge device 3 are supplied from the source 4.

The discharge device 3 is controlled in response to the percentage of modulation of the oscillations supplied to the antenna 1. This is effected by means of a suitable rectifier circuit comprising 60 the potentiometer 10 whereby a portion of the

modulated oscillations in the transmitter output circuit are converted to a modulated unidirectional electromotive force on resistance 10. This rectifier circuit comprises a suitable unilaterally conducting discharge device 11 having an anode circuit which is coupled by means of a coupling coil 12 to the inductance 2 of the transmitter output. This anode circuit also includes resistance 13, potentiometer 14, potentiometer 10, and the winding of a relay 15. The resistance 13 is of 10 such a value that the external resistance of the rectifier circuit is many times greater than the internal resistance of the discharge device 11. The relay 15 controls the energizing circuit of a suitable indicating device such as a neon lamp 16. During normal operation the current in the winding of relay 15 is sufficient to maintain the armature of this relay in its attracted position whereby the indicating device 16 is operated to indicate the presence of high frequency oscillations on the antenna 1.

A meter 17 is employed both to indicate the bias voltage supplied to the grid of the discharge device 3 and also the percentage of modulation of the oscillations supplied to the antenna 1. 25 This meter is provided with a double throw switch 18, which when in its lefthand position, connects the meter between ground and the cathode of the discharge device thereby to indicate the bias upon the grid of the discharge device 3. When 30 in its righthand position it is connected across that portion of potentiometer 10 which is included in the grid circuit of the discharge device 3, a suitable multiplier resistance 19 being included in the circuit of the meter. 35

The relay 5 is, of course, energized only when the discharge device 3 passes current and then operates to interrupt the anode circuit of the discharge device. Thus this relay acts as a buzzer to interrupt the anode circuit of the discharge 40 device successively after the device becomes conducting. A series combination of resistance 20 and capacitance 21 is connected across the contacts of the relay to eliminate sparking and in shunt to this resistance is connected a suitable 45 indicating device such as a neon lamp. This lamp responds to the voltage induced in the coil of relay 5 due to deterioration of current therein when the contacts of the relay open and thus indicates the intervals when the relay 5 is actuated, or when the discharge device 3 is conductive. 50

The gaseous conduction device 3, of course, possesses the characteristic that no current flows in the anode circuit thereof except when the 55 voltage applied to the grid is less than a predetermined negative value. When the voltage is applied to the grid is less than this value the device breaks down and passes its full value of anode current which is determined by the anode 60

voltage. When once broken down this anode current continues to flow as long as anode voltage is applied and irrespective of subsequent changes in grid voltage.

5 The operation of my device as thus constructed may now be described. In adjusting the device for operation the contact 27 on potentiometer 10 may be moved to the lower extremity of the potentiometer so that no voltage due to rectified 10 oscillations is supplied to the grid. The contact 28 is then moved to a point on resistance 7 such that the vapor electric device is just conducting. The voltage supplied to the grid by the resistance 7 may then be indicated upon the 15 meter 17 by moving the switch 18 to the left. Let us assume that this negative voltage is, for example, 4 volts. The contact 27 is now moved upward on potentiometer 10 to such a point that contact 28 may be moved to reduce the bias indicated by the meter to 3 volts without causing 20 the discharge device to break down. The precaution of first moving the contact 27 upward before making this adjustment of contact 28 is taken to avoid error due to anode current flowing 25 in the lower portion of resistance 7 when the adjustment of contact 28 is made. Switch 18 may now be thrown to the right and the contact 27 adjusted to a point on resistance 10 such that 30 the gaseous conduction device is conductive only when the voltage on resistance 10 is at its extreme minimum value due to negative peaks of modulation. Let us suppose that the voltage supplied to the grid by the resistance 10, as indicated 35 by the meter 17, is 10 volts when the contact 27 is so adjusted. This means that the average potential on the grid is 9 volts more negative than is required to make the tube non-conductive. But since the tube becomes conductive upon the 40 extreme negative peaks of modulation, it is apparent that the voltage on resistance 10 during these peaks is reduced by 9 volts, or is 1 volt. The percentage of modulation is thus indicated as 45 90%. Thus when so adjusted it will be apparent that the conduction device 3 becomes conductive whenever the percentage of modulation exceeds 90%.

Had contact 28 been adjusted to supply a bias voltage of $3\frac{1}{2}$ volts to the grid rather than 3 volts as in the previous case, other things being 50 as described, it will be apparent that the device 3 would become conductive only when the percentage modulation exceeds 95%. Thus the contacts 27 and 28 may be adjusted to cause the device 3 to become conductive, and the indicating 55 device 26 to be actuated, only when the percentage modulation exceeds a suitable desired value.

It will be observed that since unidirectional potential is applied to the anode of the discharge 60 device that the device is in readiness at all times for response at any negative peak of modulation in excess of a predetermined percentage of modulation. The device is actuated, however, only when the percentage of modulation is in excess 65 of the predetermined value since the tube 3 is immediately rendered non-conductive by the device 5 and is subsequently rendered conductive only by modulation in excess of the predetermined percentage.

70 It will be observed further that by use of the multiplier resistance 19 both the bias voltage supplied by resistance 7 and the modulated voltage supplied by resistance 10 may be indicated upon the same instrument 17 and with comparable 75 accuracies. This device preferably is provided

with two scales 29 and 30 one of which is uniformly calibrated throughout its length for indication of the voltages supplied by resistances 7 and the other of which is progressively calibrated. That is, the spacing between the successive calibrations on the other scale progressively increases from one end of the scale to the other. This scale is employed when the switch 18 is in the righthand position and indicates the percentage of modulation. The percentage of 10 modulation is of course dependent upon the ratio of the difference between bias voltage supplied to the grid and the bias voltage necessary to render the discharge device non-conductive to the average voltage supplied to the grid by the 15 resistance 10 when the device is just actuated on the negative peaks of modulation. The rate of change of this ratio progressively decreases with increase of the voltage on resistance 10 with the result that the progressively calibrated scale 20 may be employed thereby rendering possible greater accuracy of the readings of the higher percentages of modulation. This is an extremely desirable characteristic of the apparatus since small changes in the percentage of modulation 25 are more important at the higher percentages than is the case where the percentage of modulation is small.

The calibration of the scale 30 is dependent upon a certain fixed setting of the contact 28. 30 With the contact in this fixed position the percentage of modulation of the oscillations supplied to the transmitter may be determined at any time by moving the contact 27 downward to a point where lamp 26 lights and then reading 35 the percentage of modulation directly from the scale 30. If it be desired to utilize a different bias upon the discharge device 3 then a different scale 30, or suitable calibration chart may be employed.

To secure maximum accuracy of the apparatus the voltage chosen in the operation of the discharge device 3 should be such that the device always breaks down on the linear part of the grid-voltage anode-voltage breakdown characteristic. Since both the anode and grid bias voltages for discharge device 3 are obtained from the same source, variations in this source have little or no effect upon the accuracy of readings. By proper choice of the discharge device employed 50 and the gas employed therein the effects of temperature variations are also minimized or eliminated.

A meter 31 is employed for the purpose of indicating the amount of rectified current flowing 55 in the circuit of discharge device 11. Choke coil 9 is provided to prevent the passage of high frequency oscillations from the coil 2 to the grid of the discharge device 3.

In Fig. 2 I have shown a modification of my 60 invention to permit measurement of either the negative peaks or positive peaks of modulation. The equipment provided in accordance with this modification differs from that shown in Fig. 1 only in that a reversing switch 32 is provided to 65 reverse the connections of the resistance 19 in the grid circuit of the discharge device 3, and similarly a reversing switch 33 is provided in the circuit of the meter 17 to permit correct reading of the instrument when the switch 18 is in its righthand position and the switch 32 is in its lower position.

To indicate the positive peaks of modulation the switch 32 is in its lower position and the normal bias on the grid is set at such a large 75

value that the device 3 becomes conductive only on the positive peaks of modulation. For example, let us assume as before, that the discharge device becomes conductive when the negative voltage supplied to the grid is 4 volts or less and that the average voltage supplied by the resistance 10 is 10 volts. Contact 28 may then be adjusted, for example, at such a point that the voltage supplied to the grid by resistance 7 is 10 23 volts. Since this voltage now is in opposed relation to that supplied by the resistance 10 the average voltage on the grid is minus 13. However, when the voltage on resistance 10 is 90% modulated or more the voltage upon the grid 15 will be reduced to minus 4, or less, upon the positive peaks of modulation. Thus the lamp 26 will be lighted whenever the modulation exceeds 90%.

To ascertain an unknown percentage of modulation of the voltage on resistance 10 the contact 27 may be moved upward until lamp 26 lights at which instant the percentage modulation may be read directly from the scale 38 of the meter 17.

While I have shown particular embodiments 25 of my invention it will of course be understood that I do not wish to be limited thereto since many different modifications may be made both in the circuit arrangement and in the instrumentalities employed, and I contemplate by the 30 appended claims to cover any such modifications as fall within the true spirit and scope of my invention.

What I claim as new and desire to secure by Letters Patent of the United States, is,—

35 1. In combination, a gaseous conduction device having an anode, a cathode and a grid, said device being adapted to break down and pass current between its anode and cathode only when the potential applied to said grid is less than a predetermined negative value, means to supply unidirectional voltages to said grid and anode of such values that said device is conductive, means to supply a modulated unidirectional voltage to said grid with such polarity as to render 40 said conduction device non-conductive whereby said device becomes conductive only when the modulation of said unidirectional voltage exceeds a certain percent, means whereby the unidirectional voltage applied to said anode is repeatedly 45 interrupted during the interval when said conduction device is conductive whereby said conductive device is conductive only during peaks of modulation, and means responsive to current in said anode operable only when said modulation peaks exceed a certain percentage modulation.

50 2. In combination, a gaseous conduction device having an anode, a cathode and a grid, said device being adapted to break down and pass current between its anode and cathode only when the potential applied to said grid is less than a predetermined negative value, means to supply unidirectional voltages to said grid and anode of such values that said device is conductive, means 55 to supply a modulated unidirectional voltage to said grid with such polarity as to render said conduction device non-conductive whereby said device becomes conductive only when the modulation of said unidirectional voltage exceeds a certain percent, a relay having its winding and contacts connected in series with said anode repeatedly to interrupt said anode circuit whenever 60 said conduction device is conductive thereby to

render said conduction device non-conductive after peaks of modulation exceeding said certain percentage of modulation have transpired, and indicating means responsive to operation of said relay.

5 3. In combination, a gaseous conduction device having an anode, a cathode and a grid, said device being adapted when anode operating voltage is applied thereto to change from a non-conducting condition to a conducting condition 10 at a certain value of grid voltage, means to supply a continuous unidirectional operating voltage to said anode, means to supply a bias voltage to said grid differing from said certain value thereby to maintain said device in one of said two conditions, means to supply a modulated unidirectional voltage to said grid in series with said bias voltage whereby said conduction device changes to the other of said two conditions only when the percentage of modulation of said modulated 15 unidirectional voltage exceeds a predetermined value, and means whereby said conductive device is restored to said one condition after said percentage of modulation exceeding said predetermined value is reduced to a value less than said 20 predetermined value.

4. In combination, a source of unidirectional voltage subject to variation, a gaseous conduction device having an anode connected to the positive side of said source, a grid connected to the negative side of said source, and a cathode connected to an intermediate point on said source, means to maintain said connection to said anode when said conduction device is in non-conductive condition, and successively to interrupt said connection when said device is in conductive condition, 30 means to supply additional modulated unidirectional voltage to said grid, the percentage modulation of said additional voltage being such that said device changes from one of said conditions 35 to the other and all of said voltages having values such that said conduction device changes condition in response to said modulation on a linear portion of its grid voltage anode voltage breakdown characteristic, irrespective of variations to 40 45 which said source is subjected, and means to indicate breakdown of said device.

5. In combination, a gaseous conduction device having an anode, a cathode and a grid, means to supply continuous unidirectional anode operating voltage to said device when said device is in non-conducting condition and interrupted anode operating voltage to said device when said device is in conducting condition, means to supply a bias voltage to said device having a value such 55 that said device is in one of said conditions, means to supply an additional modulated unidirectional voltage to said grid, means to vary said last voltage to a value such that said device changes from said one condition to the other upon occurrence 60 of modulation peaks, indicating means responsive to conduction of said conduction device, a unidirectional voltage responsive indicating device having a scale progressively calibrated in terms of percentage of modulation, and means to connect said voltage responsive indicating device to indicate said modulated unidirectional voltage whereby for a given value of said bias voltage the percent of modulation of said modulated unidirectional voltage may be read directly from 65 70 said scale and with increasing accuracy toward the higher percentages of modulation.

GEORGE W. FYLER.
